UNITED STATES PATENT OFFICE.

JOSEPHINE A. RECKTENWALD, OF CANASTOTA, NEW YORK.

DESIGN FOR A FALSE BOTTOM FOR COOKING UTENSILS.

SPECIFICATION forming part of Design No. 34,167, dated March 5, 1901.

Application filed February 4, 1901. Serial No. 46,032. Term of patent 7 years.

To all whom it may concern:

Be it known that I, JOSEPHINE A. RECKTENWALD, a citizen of the United States, residing at Canastota, in the county of Madison, in the 5 State of New York, have invented and produced a new and original Design for False Bottoms for Cooking Utensils, of which the following is a specification, reference being had to the accompanying drawings, forming 10 a part thereof.

Referring to the drawings, Figure 1 is a top plan view of the false bottom. Fig. 2 is a bottom plan view thereof. Fig. 3 is an edge view looking at it from either the upper or lower 15 side of the view shown in Fig. 2. Fig. 4 is a view in line xx , Fig. 3.

As shown in the drawings, the leading or material feature of my design consists in a 20 perforated convex disk a , provided upon its lower face with brackets b , extending under

the lower face thereof. The brackets b , respectively made of continuous pieces of wire, are secured in the outer edge of the disk and extend toward the center of the disk, where they are curved, as at c , as shown in Fig. 2, 25 the whole forming a unique and unitary article of manufacture.

Having described my invention, what I claim, and desire to secure by Letters Patent, is—

The design for a false bottom for cooking utensils, substantially as herein shown and described.

In witness whereof I have hereunto set my hand this 31st day of January, 1901.

JOSEPHINE A. RECKTENWALD.
